US0D1094093S

(12) **United States Design Patent** (10) **Patent No.:** **US D1,094,093 S**
(45) **Date of Patent:** **** Sep. 23, 2025**

(54) **VALVE**

(71) Applicant: **Gehl Foods, LLC**, Germantown, WI
(US)

(72) Inventors: **Michael Sowieja**, Richfield, WI (US);
Thomas Mitchell, Chicago, IL (US);
Anders Olof Rostlund, Chicago, IL
(US)

(73) Assignee: **GEHL FOODS, LLC**, Germantown,
WI (US)

(**) Term: **15 Years**

(21) Appl. No.: **29/827,333**

(22) Filed: **Feb. 18, 2022**

Related U.S. Application Data

(60) Continuation of application No. 29/666,495, filed on Oct. 12, 2018, now Pat. No. Des. 944,054, which is a continuation of application No. 29/553,384, filed on Feb. 1, 2016, now Pat. No. Des. 830,768, which is a division of application No. 29/501,023, filed on Aug. 29, 2014, now abandoned.
